THORNTON J. CORWIN, OF SAN FRANCISCO, CALIFORNIA, ASSIGNOR TO ILLINOIS-PACIFIC GLASS CO., OF SAN FRANCISCO, CALIFORNIA, A CORPORATION OF CALIFORNIA.

CORRUGATED-FIBER-BOARD BOX.

1,097,390.

Specification of Letters Patent. Patented May 19, 1914.

Application filed September 24, 1912. Serial No. 722,049.

To all whom it may concern:

Be it known that I, THORNTON J. CORWIN, a citizen of the United States, residing in the city and county of San Francisco and State of California, have invented new and useful Improvements in Corrugated-Fiber-Board Boxes, of which the following is a specification.

My invention relates to corrugated fiber-board shipping boxes for glassware or fragile merchandise.

To meet the demand for light-weight shipping cases for shipping heavy, fragile merchandise by freight, considerable difficulty has been experienced in making a fiber-board or paper shipping case which will have sufficient strength and rigidity and at the same time protect the contents from breakage in transit. The present invention solves the problem in a practical, economical manner.

Having reference to the accompanying drawings, Figure 1 is a perspective of the box illustrating the invention. Fig. 2 is an enlarged cross section of the box material.

This invention consists of two or more layers A—A', of corrugated fiber-board, placed face to face and on opposite sides of the central backing or sheet 2, to which central backing sheet 2 the corrugations of the sheets A—A' are firmly attached throughout their entire length by some suitable adhesive preparation; then over each of the corrugated layers A—A' is secured an outside surfacing and finishing sheet 3 of stiffish material. These five sheets A, A', 2 and 3—3 make a double sheet of great rigidity and strength suitable for box purposes and at the same time give an enhanced degree of resiliency and elasticity so as to reduce the liability to breakage or other injury of the contents.

Owing to the thickness of the double cor-

rugated layers, with the single intermediate backing 2 and facing sheets 3, and in order to secure a square corner on the box when the flaps are folded into place, it is found that in practice the old style of crease or score would not answer. Therefore, I originated a wide crease, indicated at 5, equal in width to the thickness of the corrugated board, so that when the panels constituting the flaps of the box are bent at right angles, the folded parts will easily adjust themselves to one another without breaking the creased portions or bending or bulging the sides of the box.

Having thus described my invention, what I claim and desire to secure by Letters Patent is—

As a new article of manufacture, corrugated fiber-board for shipping boxes and the like, composed of a central base sheet, a corrugated sheet on each face of said base sheet and secured thereto, and a facing sheet disposed over and secured to each corrugated sheet, each of the corrugated sheets, at intervals, having several of the corrugations straightened out so as to provide flattened parts which are uninterruptedly secured to opposite faces of the base sheet and which in turn have the respective facing sheets uninterruptedly secured to said flattened parts, whereby hinge connections of five-ply and solid cross-section and of widths equal to the combined widths of the several flattened corrugations are provided between the corrugated parts of the board.

In testimony whereof I have hereunto set my hand in the presence of two subscribing witnesses.

THORNTON J. CORWIN.
